United States Patent Office.

N. T. DRAKE, OF HIGH POINT, NORTH CAROLINA.

Letters Patent No. 95,330, dated September 28, 1869.

IMPROVED MEDICAL COMPOUND.

The Schedule referred to in these Letters Patent and making part or the same.

I, N. T. DRAKE, M. D. of High Point, county of Guilford, State of North Carolina, have invented a certain Improved Medical Compound or Liniment, of which the following is a specification.

Take of—

Carbolic acid, one drachm;
Tincture of capsicum, one ounce;
Tincture of opium, half ounce;
Spirits of camphor, half ounce;
Chloroform, one ounce;
Aqua ammonia, half ounce;
Oil of sassafras, two drachms;
Oil of cinnamon, one drachm;
Alcohol, four ounces.

Mix by first putting oil of sassafras, oil of cinnamon, and alcohol in a bottle, and let it stand thirty minutes. Then add all the other ingredients, and shake well every hour for four hours, at the end of which time it will be ready for use.

The liniment is a safe, certain, and speedy relief for neuralgia, rheumatism, headache, toothache, sprains, bruises, and spinal irritations, to be used by moisten-

ing a piece of flannel in the liniment, and applying to the parts affected.

Relief is certain in from ten seconds to five minutes.

Administered into the stomach, it is a most excellent and safe remedy for spasmodic colic, dysentery, diarrhea, and chills and fever.

Dose for an adult, one fluid-drachm in a wineglassful of water.

I do not claim any peculiar chemical or medicinal properties of the medicines named above.

I claim as my invention—

1. The mode of compounding the several ingredients into a liniment, and applying and administering the same as described above.

2. The medical compound produced by combining carbolic acid with an essential oil and one or more tinctures, such as above named, or their medicinal equivalents.
